UNITED STATES PATENT OFFICE.

CHARLES P. SCHLEGEL, OF ROCHESTER, NEW YORK, ASSIGNOR TO SCHLEGEL MANUFACTURING CO., OF ROCHESTER, NEW YORK, A CORPORATION OF NEW YORK.

ROBE-STRAP.

1,268,500.

Specification of Letters Patent. Patented June 4, 1918.

Application filed January 2, 1917. Serial No. 140,058.

To all whom it may concern:

Be it known that I, CHARLES P. SCHLEGEL, of Rochester, in the county of Monroe and State of New York, have invented certain new and useful Improvements in Robe-Straps; and I do hereby declare the following to be a full, clear, and exact description of the same, reference being had to the accompanying drawings, forming a part of this specification, and to the reference characters marked thereon.

My present invention relates to straps which may be attached at one or both ends to any support and has for its particular object to provide a strap suitable for attachment to the backs of automobile seats for the purpose of holding robes or wearing apparel. A further purpose is to provide a neat and durable means for finishing the ends of the strap. To these and other ends the invention consists in certain improvements and combinations of parts, all as will be hereinafter more fully described, the novel features being pointed out in the claims at the end of the specification.

In the drawings:

Figure 1 is a fragmentary elevation showing a strap constructed in accordance with my invention attached to a support;

30 Figs. 2, 3, 4 and 5 are views of one end of the strap showing successive steps in the manufacture thereof;

Fig. 6 is a perspective view of one of the attaching plates;

35 Fig. 7 is a similar view of a form of finishing plate for securing over the end of the strap;

Fig. 8 is an enlarged longitudinal sectional view of one end of the strap on the 40 line 8-8 of Fig. 1;

Fig. 9 is a sectional view on the line 9-9 of Fig. 8;

Fig. 10 is a similar view on the line 10-10 of Fig. 8;

45 Fig. 11 is a plan view of one end of the strap;

Figs. 12, 13 and 14 are views showing successive steps in the manufacture of a modified structure;

50 Fig. 15 is a sectional view on the line 15-15 of Fig. 12;

Fig. 16 is a view similar to Fig. 10 showing the modified structure, on the line 16-16 of Fig. 14, and

Fig. 17 is a detail longitudinal sectional view of another modified structure.

Similar reference characters throughout the several views indicate the same parts.

A strap constructed in accordance with the present invention is particularly adapted for use on the backs of automobile seats for the purpose of holding robes, coats or other articles of wearing apparel, and embodies generally two attaching members or plates connected by a body of flexible material, preferably a single strand of cord passing through apertures in the plates and forming a plurality of windings, the free ends being tied to the plates or otherwise secured. As both ends of the strap are preferably alike I have shown one end only in Figs. 2 to 5, in which the attaching plate is shown as formed with an enlarged attaching end 1 provided with apertures 2 through which securing screws may pass, and a narrow portion 3 having an aperture 4 extending therethrough. The edge of the aperture 4 against which the cord pulls is rounded by bending back the portion 5 of the material removed in forming the aperture, as shown in Fig. 6, thereby doing away with any rough edge which might fray the cord.

The winding A is inclosed by a layer or wrapping of cord 6 wound spirally thereon in several layers until the strap is of the proper diameter, this wrapping extending beyond the end of the body winding and around the narrow portion 3 of the attaching member (Fig. 3). The strap is then covered by a tubular braid 7 (Fig. 4) which extends beyond the attaching plate at each end. The free ends of the braid are cut off a short distance beyond the attaching plate, then folded back upon the plate in which position they may be secured by sewing or by other means.

In order to protect the braid where it extends over the edge of the attaching plate, I preferably employ a finishing member or plate 8 covering each attaching plate and provided with a marginal flange extending over the edge of the latter. The finishing plate is provided with apertures 11 registering with the apertures 2 in the attaching plate to receive screws 12 by means of which the strap may be attached to any desired support. The ends of the flange 9 converge and increase in width as shown in Fig. 7 and at

their ends they are gradually rounded into the attaching plate to properly fit around the reduced portion 10 (Fig. 5) of the strap where they are bent toward each other for the purpose of securing the finishing plate on the strap, as shown in Fig. 9. Ears 13 may be provided on the flanges at opposite ends thereof, of such a length as to just meet when the flanges are bent inwardly, thereby making the finishing member more secure.

In the modified structure shown in Figs. 12 to 16, the attaching plate 1 is formed with upstanding ears 14 and the free end 16 of the braid is secured after folding it back, by means of a plate 15 placed over it, the plate being held in place by bending the ears 14 inwardly over the edge of the plate. The latter is positioned so that apertures 17 therein register with the apertures 2 in the plate 1, thus permitting the passage of the securing screws.

In the construction shown in Fig. 17 the finishing plate 18 is U shape and the attaching end of the strap is included between the parallel portions of the plate which are provided with registering apertures to receive an attaching screw or screws 19 passing therethrough.

I claim as my invention:

30 1. A strap comprising an attaching member, and a body of flexible material connected thereto, a cover extending over the body and attaching member and having an end extending beyond and folded back upon the attaching member, and means for securing the end in its folded position.

40 2. In a strap, the combination with an attaching member, and a body of flexible material connected thereto, of a cover extending over the body and attaching member and having an end extending beyond and folded back upon the attaching member, means for securing the folded end, and a finishing member covering the attaching member and having a portion extending over the edge of said member.

45 3. In a strap, the combination with an attaching member, and a body of flexible mate-

rial connected thereto, of a cover extending over the body and attaching member and having a portion doubled back upon the attaching member, means for securing the doubled portion, a finishing member covering the attaching member having a flange enclosing the edge of said member and the ends of the strap.

4. In a strap, the combination with an attaching plate having an aperture, the material removed in forming the aperture being bent to form a rounded edge, of a body of flexible material passing through the aperture and drawing against said rounded edge.

5. In a strap, the combination with an attaching member having an aperture at one end, a body composed of a plurality of cords extending through the aperture, and a wrapping covering the body and extending beyond the end of the latter onto the attaching member, of a cover extending over the wrapping and attaching member and having an end folded upon the attaching member, and means for securing the folded end.

6. In a strap, the combination with an attaching member having ears thereon, and a body of flexible material connected thereto, of a cover extending over the body and attaching member and having an end extending beyond and folded back upon the attaching member, and a securing plate placed over the end of the cover and held by bending down the ears on the attaching plate, the attaching plate and securing plate being provided with registering apertures to receive attaching devices.

7. In a strap, the combination with an attaching member comprising a body having a reduced portion at one side thereof provided with an opening, of flexible material passing through the aperture, and a finishing member covering the attaching member and having a portion embracing the edge of said attaching member, the finishing member and enlarged portion of the attaching member being provided with registering apertures to receive attaching devices.

CHARLES P. SCHLEGEL.
